[57] CLAIM

The ornamental design for a food cup, substantially as shown and described.

DESCRIPTION

FIG. 1 is a front elevational view of a food cup illustrating our new design; the opposite side being substantially a mirror image thereof;

FIG. 2 is a side elevational view thereof;

FIG. 3 is a top plan view thereof;

FIG. 4 is a bottom plan view thereof;

FIG. 5 is a side elevational view thereof; and

FIG. 6 is an enlarged sectional view taken along line 6—6 of FIG. 1.

FIG. 3

FIG. 2

FIG. 1

FIG. 4

FIG. 5

FIG. 6
